UNITED STATES PATENT OFFICE.

IRA A. SHALER, OF NEW YORK, N. Y.

CONCRETE CONSTRUCTION.

SPECIFICATION forming part of Letters Patent No. 654,683, dated July 31, 1900.
Application filed March 9, 1900. Serial No. 7,977. (No model.)

To all whom it may concern:

Be it known that I, IRA A. SHALER, a citizen of the United States, residing in the borough of Manhattan, city of New York, State of New York, have invented certain new and useful Improvements in Concrete or Similar Constructions, of which the following is a specification, reference being had to the accompanying drawings, forming a part hereof.

10 In the construction of walls, beams, floors, &c., of concrete, clay, or other similar material for buildings, bridges, retaining-walls, and other uses it is common to incorporate with the concrete, clay, or other material metallic rods or bars particularly for the purpose of giving to the compound structure a greater capacity to resist strains than is possessed by the concrete or clay alone. In order to effect this increase in strength, the 15 arrangement of the metallic rods or bars must be such as to prevent the failure of the concrete, clay, or other similar material by either tensile, compressive, or shearing stresses, which implies that the bond between the concrete, clay, or other similar material and the rods shall not be broken; also, that certain members of the metallic framework be so disposed as to intersect possible planes of shearing rupture in the concrete, clay, or other 20 similar material. Unless means are taken to prevent it the bond between such rods or bars and the concrete or clay or other like material is liable to become broken, whereby a serious loss of strength of the combined structure is occasioned. Various means have been 25 hitherto devised for the purpose of preventing failure or weakening of the construction due to shear in the concrete, clay, or other similar material or to the breaking of the bond and consequent slipping of the rod or bar within the concrete, clay, or other similar material; but such means have been inefficient or have left certain portions of the skeleton liable to rust from not being completely surrounded with concrete, have been unduly expensive by reason of the fact that special shapes have been required to be given to the rods or bars, have required the reduction of cross-section of the rods by the punching of holes, &c., and have provided against the slipping of the rod in the concrete or the

shear in the concrete only without accomplishing any additional purpose.

It is the object of this invention to improve concrete or other like constructions of the class referred to, and particularly to provide improved means for preventing the breaking of the bond between the rods or bars and the concrete or other material, and also to provide improved means for preventing the failure of the construction by rupture of the concrete, clay, or other material due to either compressive, tensile, or shearing stresses. These means are not only thoroughly efficient for the purpose intended, but provide welded joints between the members, which can readily be completely covered by concrete and are capable of application as the work of construction progresses and without requiring any previous preparation of the rods or bars employed. Moreover, no reduction of the cross-section of the bars is required, and they may frequently be so arranged that one member will through its rigid connection with another be not only able to bind together two portions of the construction or strengthen the concrete, clay, or other similar material against rupture, but also prevent the slipping in the concrete of the member with which it is connected.

In accordance with the invention any longitudinal or main member of the metal part of the structure may have welded thereto one or more subordinate or cross members which are disposed at an angle, preferably approaching a right angle, with the longitudinal or main member. As all of these parts are embedded in the concrete, it is impossible for any slip to occur between the rods and the concrete at or near the points of union. To still further guard against the probability of any slip, the subordinate or cross members and the longitudinal or main members themselves, especially where the distances between the cross members are great or where no cross members exist, may be upset, and thus formed with a bulbous enlargement or swelling, which is integral with the rod itself.

The invention is illustrated for purposes of explanation in the accompanying drawings, in which—

Figure 1 is a sectional view of a beam or

floor which embodies the invention, a portion of the supporting-wall being shown. Fig. 2 is a similar view showing an extension of the arrangement shown in Fig. 1. Fig. 3 is 5 a similar view illustrating the application of the invention to a retaining-wall.

In the several figures of the drawings the main or longitudinal members *d* of the metal structure are represented as embedded in the 10 concrete, clay, or other material *b*. As represented in both Figs. 1 and 2, there may be welded to any main or longitudinal member at suitable intervals subordinate or cross members *c*, which are disposed at an angle 15 with the main or longitudinal member, such angle preferably approaching a right angle. The welded joints are represented at *a*. They may include all of the joints in the skeleton or a portion of such joints only. As shown 20 in Fig. 2, where a second longitudinal member *d* is indicated, the longitudinal members may be variously arranged within the concrete according to the particular strain to which any part of the structure is to be subjected. As indicated in Fig. 3, the main members 25 may be welded, as at *f*, to other principal members or rods *c'*, which extend through the structure in a direction transverse to that of the rods *d*. As represented in Fig. 3, 30 braces or ties *e* may be welded at one or both ends to the main rods of the wall and foundation, as shown at *a*, being embedded in the concrete of the buttress. Each short, subordinate, or cross member *c* is preferably upset 35 at some point, as at *c'*, to form an integral enlargement on such rod for the purpose of securing a firmer bond, and the main rods may also be similarly upset, as at *a'*, for the same purpose, especially where the distances between the cross rods or members are comparatively large or where there are no cross 40 members.

It will be evident that the welding of the joints and the upsetting of the rods can be

accomplished readily as the work of construction progresses and that consequently it is possible to use for the purpose ordinary simple rods in the condition in which they are delivered from the drawing-rolls without requiring any further preparation for the intended use. 45

Other advantages of the improved construction will be readily understood. Thus the metal skeleton is more or less rigid and is itself therefore better able to carry loads 50 in case of the rupture of the concrete or other material in which it is embedded. Furthermore, such skeleton possesses greater efficiency in assisting the concrete while intact to carry loads or resist strain not only by 55 providing against shear or rupture due to other causes in the concrete itself, but by securing a more perfect union between the concrete and the metal skeleton, since the welded joints prevent any movement of the 60 rods within the concrete, and the rods and concrete body are caused to act together as one body. It will also be noted that by welding the members together no diminution of 65 the cross-section of any member is occasioned and also that the welded joints of the metal skeleton can be completely covered with the concrete, so that they are not exposed to the action of rust. 70

I claim as my invention—

In a concrete or other like construction, 75 the combination with the concrete or other like body, of a metal skeleton embedded therein, said skeleton comprising main or longitudinal members and subordinate or cross members welded thereto at intervals, substantially as shown and described.

This specification signed and witnessed this 6th day of March, A. D. 1900.

IRA A. SHALER.
